CLAIM

The ornamental design for a protective cover skin for electronic device, as shown and described.

DESCRIPTION

FIG. 1 is a front, top, and left perspective view of a protective cover skin for electronic device, showing the claimed design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a rear, bottom, and left perspective view thereof;

FIG. 9 is an exploded rear, top, and left perspective view of the protective cover skin for electronic device; and,

FIG. 10 is an exploded front, top, and right perspective view of the protective cover skin for electronic device with a top portion open in use.

The letters and period shown in broken lines in FIGS. 1, 2, and 10 illustrate portions of the protective cover skin for electronic device that form no part of the claimed design. The broken lines shown in FIGS. 3 and 9 depict portions of the protective cover skin for electronic device that form no part of the claimed design. The broken line showing of an electronic device in FIG. 10 depicts environment and forms no part of the claimed design.
